UNITED STATES PATENT OFFICE.

STELLA BRANDT, OF NEW YORK, N. Y., ASSIGNOR TO WAITE CARPET COMPANY, OF OSHKOSH, WISCONSIN, A CORPORATION OF WISCONSIN.

DESIGN FOR A RUG.

Application filed June 11, 1928. Serial No. 27,074. Term of patent 3½ years.

To all whom it may concern:

Be it known that I, STELLA BRANDT, a citizen of the United States, residing at New York city, in the county of New York and State of New York, have invented a new, original, and ornamental Design for Rugs, of which the following is a specification, reference being had to the accompanying drawing, forming part thereof.

The figure is a plan view of approximately one half a rug showing my new design, the opposite one half being a repetition of the detailed illustration.

I claim:

The ornamental design for a rug, as shown and described.

STELLA BRANDT.
